(75) Inventor: **Hideyasu Kataoka**, Tokyo (JP)

(57) **CLAIM**

(73) Assignee: **Mitsubishi Denki Kabushiki Kaisha**, Tokyo (JP)

The ornamental design for a front section of an automotive navigation system, as shown and described.

(**) Term: **14 Years**

DESCRIPTION

(21) Appl. No.: **29/139,685**

(22) Filed: **Apr. 5, 2001**

(30) **Foreign Application Priority Data**

Oct. 18, 2000 (JP) 2000-029570

(51) LOC (7) Cl. **10-04**

(52) U.S. Cl. **D10/80; D10/65**

(58) **Field of Search** D10/65, 80; D14/100, D14/104, 106, 107; 345/104, 133, 156, 168, 173, 87, 901-905; 348/180, 184, 325, 739; 364/444, 499; 342/419, 457, 357

(56) **References Cited**

FIG. 1 is a front elevational view of a front section of an automotive navigation system, showing our new design; FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a cross-sectional view thereof, taken along line 7—7 of FIG. 1, with the internal system omitted; and, FIG. 8 is a cross-sectional view thereof, taken along line 8—8 of FIG. 1, with the internal system omitted.

The broken lines in the Figures are for illustrative purposes only and form no part of the claimed design.
